F. GARRISON.
SWIVEL FOR ELECTRICAL CONDUCTORS.
APPLICATION FILED NOV. 8, 1915.

Patented Sept. 26, 1916.

Inventor,
Flint Garrison.
By Rakewell & Chase Atty's.

UNITED STATES PATENT OFFICE.

FLINT GARRISON, OF ST. LOUIS, MISSOURI.

SWIVEL FOR ELECTRICAL CONDUCTORS.

1,199,172.

Specification of Letters Patent. Patented Sept. 26, 1916.

Application filed November 8, 1915. Serial No. 60,273.

To all whom it may concern:

Be it known that I, FLINT GARRISON, a citizen of the United States, residing at St. Louis, Missouri, have invented a certain new and useful Improvement in Swivels for Electrical Conductors, of which the following is a full, clear, and exact description, such as will enable others skilled in the art to which it appertains to make and use the same.

This invention relates to devices that are used for connecting electrical conductors together.

One object of the invention is to provide a device that will prevent an electrical conductor from breaking when one portion of same is twisted or turned with relation to its other portion.

Another object is to provide a device that can be applied easily to a flexible conductor, such, for example, as a telephone cord or a lamp cord, so as to prevent the conductor from twisting or becoming snarled, due to frequent handling of the instrument or object to which the conductor is connected.

Other objects and desirable features of my invention will be hereinafter pointed out.

Briefly described, my invention consists in a swivel for electrical conductors that comprises two members joined together in such a manner that one can turn or rotate relatively to the other and coöperating contacts on said members that always remain in engagement with each other when said members are assembled, said contacts being provided with binding screws, or other suitable means for enabling the adjacent ends of an electrical conductor to be connected to the contacts.

Figure 1 of the drawings is a longitudinal sectional view of a swivel constructed in accordance with my invention that is designed for use with a flexible conductor composed of a plurality of strands of wire. Fig. 2 is a top plan view of one member of the device; and Fig. 3 is a top plan view of the other member of the device.

The shape of the two coöperating members or parts of the device and the form of the coöperating contacts on said members are immaterial, so far as my broad idea is concerned, and while I have herein illustrated my invention embodied in a swivel that is designed for use with an electrical

conductor provided with three strands of wire, I wish it to be understood that the invention is applicable to a swivel or connecting device designed for use with a conductor composed of either a single strand or a plurality of strands of wire. Furthermore, my broad idea is applicable to a swivel designed for use with a rigid electrical conductor that is apt to be subjected to twisting or torsional strains.

Referring to the drawings, which illustrate the preferred form of my invention, A and B designate two members that are provided with coöperating contacts which bear snugly upon each other when said members are assembled or connected together, as shown in Fig. 1. The contact carrying portions of both of said members are formed of rubber or some other suitable insulating material, and the coöperating contacts thereon are so designed that one member can turn or rotate freely with relation to the other member without disengaging said contacts or breaking the electrical connection between the contacts. In the form of my invention illustrated the members A and B are substantially semi-spherical shaped and the member A is provided with three segmental shaped contacts 1, 2 and 3, each of which has a binding screw 4 or other suitable device for enabling an electrical conductor to be connected thereto. The contacts 1, 2 and 3 project forwardly from the inner end of the member A and the binding screws 4 are seated in holes formed in the bottom of a recess 5 in the end face of said member A. The member B is provided with three concentrically arranged, ring-shaped contacts 1^a, 2^a and 3^a that are arranged in annular grooves 5^a formed in the end face of the member B which receive the forwardly-projecting portions of the contacts 1, 2 and 3 on the member A when the members A and B are assembled. The segmental-shaped contacts on the members A have more or less resiliency and they are so arranged that they partially surround or embrace the contact rings on the member B and exert sufficient pressure on same to form a good electrical contact when the device is in use.

The member B is preferably hollow or in the form of a shell and the portion 6 of said member that carries the contact rings 1^a, 2^a

and 3^a is preferably detachably connected to said shell by means of coöperating screw threads on the periphery of the portion 6 and on the inner side of the shell, as shown 5 in Fig. 1. Each of the contact rings on the member B is provided with an extension 7 that carries a binding screw 8, or other suitable device, so as to enable an electrical conductor to be detachably connected thereto, 10 but it will of course be obvious that various other means could be employed for connecting the wires or conductors to the contacts on the member B without departing from the spirit of my invention. The members 15 A and B are swiveled together or joined in such a manner that one member can turn or rotate freely with relation to the other member. In the device herein shown the members A and B are connected together by a 20 bolt 9 on the member A that projects through an opening in the portion 6 of the member B, the head of said bolt being permanently embedded in the member A and the nut 9^a on said bolt being arranged on the 25 inner side of the portion 6 of the member B.

The members A and B are provided at their outer ends with openings 10 through which the adjacent ends of the conductor C lead, and if the conductor is of the type that 30 is commonly used on telephones, the cord or strand 11 of same, which is used to take up the strain on the wires of the conductor, can be connected to the bolt 9 on the member A and to a ring 12 that is swiveled on said bolt 35 between the nut 9^a thereon and the portion 6 of the member B through which the bolt passes.

To install the device the conductor C is first cut in two and the strands or wires 40 in one portion of same are securely connected to the contacts 1, 2 and 3 on the member A by means of the binding screws 4, it, of course, being understood that the members A and B have been previously dis- 45 assembled or taken apart. The shell or body portion of the member B is then un- screwed from the portion 6 of said member so as to enable the strands or wires in the other portion of the conductor C to be con- 50 nected to the extensions 7 on the ring- shaped contacts 1^a, 2^a and 3^a on the mem- ber B and thereafter the portion 6 of the member B is slipped over the bolt 9 and secured in place by tightening the nut 9^a, 55 the act of arranging the portion 6 in oper- ative position causing the segmental- shaped contacts on the member A to be pressed tightly against the ring- shaped contacts on said portion 6. The assem- bling 60 of the device is completed by screwing the shell or body portion of the member B onto the portion 6 of said member.

A device of the construction above de- 65 scribed can be used with any kind of an electrical conductor, either rigid or flexible,

that is subjected, or liable to be subjected, to twisting strains, and in view of the fact that it comprises two portions that are free to turn or revolve with relation to each other, it eliminates the possibility of the conductor becoming broken, due to abnormal, torsional strains, or from becoming twisted out of shape.

While the device is capable of general use, it is particularly adapted for use on a 75 flexible conductor, such, for example, as a telephone cord or a lamp cord, owing to the fact that it prevents such a conductor from becoming snarled or twisted, due to frequent handling of the instrument or object 80 to which the conductor leads.

Having thus described my invention, what I claim, and desire to secure by Letters Patent, is:

1. A swivel connecting device for electri- 85 cal conductors composed of two members pivotally connected together so that one can turn or rotate with relation to the other, a plurality of segmental-shaped resilient contacts on one member, a plurality of annular 90 grooves in the other member for receiving said contacts, and ring-shaped contacts in said grooves that are embraced or partially surrounded by said segmental-shaped contacts when the device is in use. 95

2. A swivel connecting device for electri- 100 cal conductors composed of two members that are provided with coöperating contacts which always remain in engagement with each other when said members are as- sembled, one of said members having a re- 105 movable portion provided with a plurality of annular spaced grooves in which said contacts are arranged, and a device on the other member that projects through said removable portion and thus joins said mem- bers together so that one can turn or rotate with relation to the other. 110

3. A swivel connecting device for electri- 115 cal conductors, comprising two members, one of which is provided with a removable portion having a plurality of annular spaced grooves therein of different diam- 120 eters, a plurality of ring-shaped contacts arranged edgewise in said grooves, resilient, segmental- shaped contacts on the other member that project into said grooves and coöperate with the vertical side portions of said ring-shaped contacts, a pivotal connec- 125 tion between said members, and means for enabling electrical conductors to be detach- ably connected to said contacts.

4. A swivel connection for electrical con- 130 ductors consisting of two members, one of which is provided with segmental-shaped contacts that project forwardly from the end thereof, a removable portion on the other member that forms the end face thereof, annular grooves in said removable portion for receiving said segmental-shaped

contacts, coöperating ring-shaped contacts in said grooves, and a connecting device for said member rigidly connected to one member and passing freely through the removable portion of the other member.

5 In testimony whereof I hereunto affix my

signature in the presence of two witnesses, this fourth day of November 1915.

FLINT GARRISON.
